UNITED STATES PATENT OFFICE.

FRANCIS M. LECHNER, OF COLUMBUS, OHIO, ASSIGNOR TO THE CONCENTRIC ENGINE AND MANUFACTURING COMPANY, OF COLUMBUS, OHIO, A CORPORATION OF OHIO.

ROTARY ENGINE.

No. 889,247.

Specification of Letters Patent.

Patented June 2, 1908.

Application filed October 3, 1906. Serial No. 337,187.

To all whom it may concern:

Be it known that I, FRANCIS M. LECHNER, a citizen of the United States, residing at Columbus, in the county of Franklin and State of Ohio, have invented a certain new and useful Improvement in Rotary Engines, of which the following is a specification.

The object of this invention is to provide a cheap, economical and efficient rotary engine the motive power of which is steam, air or other fluid under pressure.

The invention resides in the construction herein shown and described, the invention not being confined in its practical embodiment to the precise details shown.

In the accompanying drawings—Figure 1 is a central vertical sectional view taken longitudinally with reference to the axis of motion of the driven shaft; Fig. 2 is an elevation of the left hand side as presented in Fig. 1 with the hub of the outer or rotary cylinder in section; Fig. 3 is a fragmentary elevation of the right hand standard showing the end of the lateral extension of the internal cylinder with the supply and exhaust ports therein; Fig. 4 is a vertical cross section on the line $x-x$ Fig. 1 looking to the right; Fig. 5 is a similar section on the line $y-y$ looking to the right; Fig. 6 is a sectional detail on a larger scale of the gate or valve; Fig. 7 is a sectional detail on the line $z-z$ Fig. 4; Fig. 8 is a view, partially in section, of the gate or valve removed; Fig. 9 is a plan view of the upper edge of what is shown in Fig. 8; Fig. 10 is an elevation of the left hand end of what is shown in Fig. 8. Fig. 11 is a detail side view of a packing ring used between the contiguous faces of the cylinders showing the same uncompressed; Fig. 12 is a similar view showing the ring compressed.

In the views 1 designates the internal cylinder and 2 the external cylinder. The internal cylinder is of smaller diameter generally than the internal diameter of the external cylinder so as to provide an annular chamber around the internal cylinder. The annular chamber is divided into two compartments by transverse bridges or abutments 3 and 3^a located at diametrically opposite points on the internal cylinder. The abutments are furnished with suitable packings 4 and 4^a to prevent leakage between the compartments, and each of the approaches to each of the abutments from the main surface 55 of the internal cylinder is inclined, as illus-

trated at 5 and 5^a , to prevent violent swinging motion of the valves or gates as they pass over said abutments, as hereinafter indicated.

The internal cylinder is provided with a central lateral extension 1^a. The character 6 designates the fluid pressure inlet passage in the internal cylinder. This passage is diametrically disposed except where it is deflected around the axis of the cylinder; and it is connected with the exterior of the engine by a passage 6^a through the lateral extension 1^a.

7 designates the exhaust passage. This passage is the same in form as the inlet passage and it communicates with the exterior of the engine by means of a passage 7^a in the extension 1^a. The passages 6, 6^a and 7, 7^a are, of course, independent of each other, and the passages 6 and 7 are inclined to each other so that the terminals of the same passage lie on operatively corresponding sides of the abutments, but different passages terminate on opposite sides of the same abutment, both being rather near the abutments. The two compartments between abutments thus each have an inlet and an exhaust located more than ninety degrees asunder. In order that the terminals of the inlets can lie near the abutments the inclined approach to said abutment at that side is cut out at its middle.

The external cylinder 2 is comprised of a cylindrical rim portion 2^a to which is bolted, at opposite sides, heads 2^b and 2^c. The head 2^b is provided with a central opening through which extends the lateral projection 1^a of the internal cylinder, and keyed to turn with the head 2^c is the driven or power shaft 8. This shaft is conveniently extended through the lateral projection 1^a of the interior cylinder.

The engine is supported in suitable standards 9 and 9^a the lateral projection 1^a being secured from turning by means of a set screw 9^b in the standard 9 and the shaft 8 resting to turn in suitable bearings in the standard 9^a.

10 designates the gates or valves. There are four of these gates or valves spaced equidistantly apart around the inner side of the rim of the exterior cylinder. The gates 10 are shaped to fit in sockets 2^d and are provided with pintles or spindles 10^a journaled in the heads 2^b and 2^c. The forward wall 2^e 110

of the socket is preferably made such that it takes the stress or pressure of the valve or gate, and the gate is made of such depth that the free edge of the gate does not press 5 against the surface of the internal cylinder. To prevent leakage, however, the edges and ends of the gates or valves are furnished with suitable packings 10^b and 10^c acted on by springs (see Fig. 8) to hold them against the 10 surfaces of the interior cylinder on which they run. The end packings 10^b are recessed to engage the ends of the edge packings 10^c and the end packings are held from dislodgment, but movably, by the pins 10^a, 15 as seen in Fig. 10. One end of each of the pins 10^a protrudes through the head, and each is provided with a suitable spring 11 tending to project the valve or gate into position across the compartment to close it 20 forward of the pressure. The tension of the spring 11 can be regulated by means of a rod 11^a attached to it and a set screw 11^b in a binding post 11^c through which the rod is passed.

25 Where the extension 1^a passes through the head 2^b it can be suitably packed or provided with a bushing to prevent leakage, as, for example, as seen in Fig. 1.

To prevent leakage between outer and 30 inner faces of the cylinders I provide a special construction consisting of split rings 12, 12^a and 12^b fitted in grooves in the contiguous faces of the respective cylinders. The rings are split rings, as seen in Figs. 11 35 and 12, cut as shown in Fig. 11 so as to lap when the ends are sprung inward, as shown in Fig. 12. The seats for the rings are made of smaller circumference than the ring in the condition shown in Fig. 11 so that the ring 40 will fit closely when sprung, as seen in Fig. 12. All three of the rings are backed by coil springs 13 so as to hold the ring with gentle pressure against the opposing surface. The springs of the rings 12 and 12^a can be in- 45 serted through openings from the outer side of the external cylinder, said openings being closed by screws 14.

In practice, steam, compressed air or other fluid under pressure is admitted at the passage 6^a, which, operating in the compartments between the abutments of the interior stationary cylinder and the gates or valves of the outer rotary cylinder, propels the latter. The fluid in advance of a given diametrical pair of gates or valves exhausts 55 through the passages 7 and 7^a after the other pair of gates or valves has reached or passed the terminals of said passage; and because one pair of the gates is projected across the 60 compartment in front of the terminals of the passage 6 before the other pair reaches the terminals of the exhaust, one pair of the gates is constantly opposed to and operated by the pressure.

65 As before indicated, the gates fit in the

pockets provided for them in the interior of the rotary cylinder, and as they pass over the bridges or abutments they are, by the inclined approaches, carried gently and with little or no noise outward into such pockets. 70 Likewise, when the gates pass the abutments, they are gently permitted to turn inward into position to take pressure.

It will be observed that in the engine herein shown and described the same operating fluid works with equal force upon equal areas on opposite sides of the axis of motion.

What I claim and desire to secure by Letters Patent is:

1. In a rotary engine, the combination of 80 an internal stationary cylinder provided with a central lateral extension and with a fluid pressure passage and an exhaust passage, an external rotary cylinder carrying valves to 85 work between the stationary and rotary cylinders, each of said passages opening at opposite sides of the stationary cylinder and having independent connections with the exterior of the engine through the lateral extension of the internal cylinder, and a shaft connected with the external cylinder and passing 90 through said lateral extension thereto.

2. In a rotary engine, the combination of 95 an internal stationary cylinder and an external rotary cylinder concentrically arranged and with a fluid pressure chamber between them, diametrically opposite abutments on the internal cylinder dividing said fluid pressure chamber into two compartments, said 100 abutments each provided on one side thereof with a channel extending circumferentially, the interior cylinder opening into each of said compartments through said chambers, a fluid pressure passage and an exhaust passage 105 opening into each of said compartments, movable valves carried by the external rotary cylinder adapted to be successively operated on by the fluid pressure and operated by the abutments.

3. In a rotary engine, the combination of 110 an internal stationary cylinder and an external rotary cylinder arranged with a fluid pressure chamber between them, diametrically opposite abutments on the internal cylinder 115 dividing the fluid pressure chamber into two compartments, a fluid pressure passage and an exhaust passage opening into each of said compartments, said openings being more than ninety degrees apart, hinged valves carried by the external rotary cylinder, springs on the exterior of the engine for operating said valves in one direction, means for varying the tension of said springs, and means for holding the springs under different tensions. 120

4. In a rotary engine, the combination with an external rotary cylinder, of internal hinged valves or gates having spindles protruding through the cylinder, springs on the protruding spindles for operating the valves 130

or gates, means for varying the tension of said springs, and means for maintaining the springs under different degrees of tension.

5. In a rotary engine, the combination with an external rotary cylinder, of an internal hinged valve provided with a spindle, a packing at the free edge of said valve, and end packings engaging the edge packing but movable laterally independently thereof, 10 said end packings being movable longitudinally and laterally but held from dislodgment longitudinally by engagement with said spindle.

6. In a rotary engine, the combination with an external rotary cylinder, of an internal hinged valve provided with a spindle, a packing movably seated in the free edge of the valve, packings movably seated in the ends of the valve, said end packings engaging 20 the spindle and held from removal thereby, said end packings also engaging the edge packing, and said end packings being movable laterally independently of the edge packing.

25 7. In a rotary engine, the combination

with an external rotary cylinder, of an internal hinged valve or gate provided with a spindle and its free edge provided with a packing and its ends provided with packings engaging the edge packing, said end packings 30 movably held by the spindle, and springs for pressing the edge packing.

8. In a rotary engine, the combination of the internal cylinder and the external cylinder, one of the contiguous faces of which is 35 provided with an annular seat, of a split packing ring seated in said seat, and means for adjusting said ring laterally in its seat.

9. In a rotary engine, the combination of the internal cylinder and the external cylinder, one of the contiguous faces of which is 40 provided with an annular seat, of a split packing ring having a lap joint at its ends seated in said seat, said ring being normally 45 of larger diameter than said seat, whereby it must be contracted to be placed in said seat.

FRANCIS M. LECHNER.
